UNITED STATES PATENT OFFICE.

JAMES R. WALSH, OF JACKSONVILLE, FLORIDA.

CONCRETE SHIP.

1,292,173.

Specification of Letters Patent. Patented Jan. 21, 1919.

Application filed May 10, 1918. Serial No. 233,654.

To all whom it may concern:

Be it known that I, JAMES R. WALSH, a citizen of the United States, residing at Jacksonville, in the county of Duval, State of Florida, have invented certain new and useful Improvements in Concrete Ships, of which the following is a description, reference being had to the accompanying drawing and to the figures of reference marked thereon.

My invention relates to improvements in concrete ships.

In the ordinary construction of ships and especially concrete ships, great care has to be taken to reinforce or brace the ship to prevent the collapse thereof transversely or athwartship but practically no attention has been paid to the strengthening or bracing the ship against the torsional or cork-screw movement. Ships are subjected to a torsional or cock-screw movement owing to the movement or pressure of the different waves against different parts and unless this torsional strain caused thereby is provided for, there will be a movement or yielding of the ship which will crack or fracture the concrete and make the ordinary concrete ship of no commercial use. In the ordinary structure of ships, the same has been braced by transverse deck beams, while in my improved ship the deck beams extend longitudinally of the ship and the inner skin of the ship braced by longitudinal girts or beams and the outer skin braced by the usual form of ribs and intermediate frames and the whole tied together to form a solid hull.

I also provide torsional braces which may be of any number and extend from the stern to the bow spirally around the ship in both directions between the outer and inner skins and interlocked with the frame, ribs, longitudinal girts or beams and the deck beams or girts, so that the ship is braced from bow to stern against the torsional strain to prevent any substantial yielding to cause the cracking or fracture of the cement.

The object of my invention is to provide a simple and effective structure to obtain the desired results, having certain details of structure and combinations of elements hereinafter more fully set forth.

In the accompanying drawings:

Figure 1 is a side elevation of a ship 55 constructed according to my invention showing the spiral torsional braces diagrammatically:

Fig. 2 is a top plan view of Fig. 1 showing the torsional braces and bulk heads in 60 dotted lines;

Fig. 3 is an enlarged vertical sectional view taken on the line 3—3, Fig. 2;

Fig. 4 is an enlarged transverse sectional view showing one half of the ship; 65

Fig. 5 is an enlarged side elevation of a section of the ship showing the intersection of the ribs, beams, frame and torsional braces before the outer skin is applied;

Fig. 6 is a transverse vertical sectional view taken on the line 6—6, Fig. 5;

Fig. 7 is a top plan view partly in section of the forward end of a modified form of ship; and

Fig. 8 is a transverse vertical section of 75 the form of ship shown in Fig. 7.

Referring now to the drawings, 1 represents the hull of my improved concrete ship, which as shown, is of the whale back type, adapted to withstand the battering of the 80 waves. This type of ship has been usually constructed of steel and it has been found that they can be made of concrete when properly braced, to resist the torsional strain, the type of ship allowing for the 85 continuous torsional braces 2 extending from the bow to the stern of the ship. These torsional braces extend spirally around the ship in both directions and from the bow to the stern as fully shown in Figs. 90 1 and 2 of the drawings. Any number of these braces can be employed and as heretofore stated, they extend spirally around the ship in opposite directions and intersect each other at several points along the hull, 95 as shown in Fig. 2 of the drawings.

The ship as is understood, is constructed wholly of concrete, reinforced with metal and formed of the double skin type as will be hereinafter more fully described. The 100 keel 3 of the ship as shown in Fig. 4 of the drawings, is vertically disposed and formed of any number of longitudinally extending bars 4 which are covered with or wrapped with wire or expanded metal and filled in 105 with concrete, forming a keel which ex-

tends from the stern 5 of the ship to the bow. This keel can be continued upwardly forming the stem post 5' as shown in Figs. 1 and 2 of the drawings, although this could 5 be readily varied without departing from my invention.

In the ordinary ship, the deck beams extend transversely of the ship but in a concrete whale back type of ship, it has been 10 found that the ship is stronger and will withstand the torsional strain more readily by having the deck beams 6 extend longitudinally of the ship as shown in Fig. 4 of the drawings.

15 The hull of a vessel or ship constructed under my invention consists of the keel 3 of the form heretofore described. Extending upwardly from the keel at the proper intervals, are the ribs 6 which terminate at the 20 point 7 in the plane of the deck. Spaced between the ribs, are the frames 8 which are in effect ribs but are of a width considerably greater than the ribs 6, so as to form a larger surface for tying the torsional braces as will 25 be hereinafter more fully described. These frames 8 like the ribs 6, extend upwardly to the point 7 flush with the deck 9 of the ship and are formed of bars covered or wrapped with expanded metal or wire mesh 30 and filled with cement or concrete forming the rectangular frames. The bars of both the ribs 6 and frames 8 intersect the keel and are electrically welded to the bars 4 of the keel, so that when the ship is completed, the 35 reinforcing bars are practically one forming a more rigid and stronger ship.

Extending the entire length of the ship from the bow to the stern are the beams 9' which are formed of bars wrapped with expanded metal or wire mesh and filled with concrete, the bars thereof intersecting the ribs 6 and frames 9 and electrically welded. The deck beams 10 also extend longitudinally of the ship and are formed of bars 40 wound with expanded metal or wire mesh and filled with concrete. The bars of the deck beams intersect the spiral torsional braces 2 and said bars are electrically welded to the bars of the braces. The deck beams 45 10 and the beams 9 are very close together and secured to the inner faces of the said beams, ribs, frames and torsional braces, is the inner skin 11 which is formed of concrete comprising two layers of expanded metal or wire mesh and on the outside of the ribs, frames, beams and torsional braces is the outer skin 12 which is constructed the same as the inner skin and both the outer and inner skins tied to the beams, ribs, frames and 55 60 torsional braces in any desired manner in the construction thereof to form practically a solid mass with the ribs, beams, frames and torsional braces, so that there is absolutely no movement of any parts independent of each other.

The beams of the hull as shown, do not extend all the way to the deck in a vertical line, but follow the contour of the whale back form and at the point designated A the outer skin leaves the beams and follows 70 the ribs and frames to form the flat flush deck, as clearly shown in Fig. 4 of the drawings.

Intermediate the deck and the bottom of the vessel is the horizontal partition or deck 75 13 which has its beams 14 extending longitudinally of the ship, thus dividing the ship horizontally into the lower compartment 16 and upper compartment 17.

The hull of the vessel is divided transversely by a series of bulk-heads 18 shown in Figs. 2 and 3 of the drawings which extend entirely across the vessel forming the compartments 19 and the deck beams are supported by the bulk-heads and said bulk-heads are braced by the braces 20, Fig. 3. The inner skin forms the bottom of the vessel and the beams are broader to bring the inner skin in a horizontal plane as shown in Fig. 4 at 15.

90 The deck of the vessel is provided with hatch coamings 21 which are formed by metal bars the same as the ribs and beams, and the spiral braces intersect the same at the corners and the bars thereof are welded together so as to thoroughly brace the same and form practically a composite metal reinforced ship.

95 Fig. 5 shows two of the spiral braces 2 intersecting each other at a point opposite one of the frames 8 and Fig. 6 shows a cross section thereof with the several bars 8' of the spiral braces and the offset portions of the bars 9' of the frames 8, so that they may all be welded together to form a complete tie 105 between the bars of the same.

The manner in which the several ribs, beams, frames, braces and the outer and inner skin is formed, in respect to each other is not described, as the details of the method 110 of the steps of constructions would form no part of the invention.

115 While I have shown and described the double skin form of ship, it will be understood that the same principle of torsional bracing can be employed in the single skin ship used in the freight service, tankers, etc., in which the weight is an important factor. In this type of ship the torsional braces 22 are embedded within the single skin 23 of the ship and extend spirally around in both directions from the bow to the stern the same as in the double skin ship shown in Figs. 1 to 6 inclusive. In the single skin ship the torsional braces are composed of 120 any number of rods wrapped with wire or expanded metal and filled with concrete, but said braces are preferably of a flat or ribbon form. In the single skin the hatches are surrounded by a ribbon of a circular 125 130

form and designated at 24 and made of concrete, the same as the spiral braces and to which the braces are secured when they come in position to intersect the hatch as shown in Fig. 7.

Having thus fully described my invention what I claim as new and desire to secure by Letters Patent is:—

1. A concrete ship comprising a concrete metal reinforced hull, and spiral torsional braces embedded therein and extending from the bow to the stern.

2. A concrete ship comprising a concrete metal reinforced hull and spiral torsional braces embedded therein and extending in both directions from the bow to the stern.

3. A concrete ship comprising a concrete metal reinforced hull and spiral torsional braces embedded therein and tied to the metal reinforcement and extending from the bow to the stern.

4. A concrete ship comprising a concrete metal reinforced hull and spiral torsional braces embedded therein and tied to the metal reinforcement and extending in both directions from the bow to the stern.

5. A concrete ship comprising a concrete metal reinforced hull, the beams extending longitudinally thereof, and spiral torsional braces embedded in the hull and tied to the beams.

6. A concrete ship comprising a concrete metal reinforced hull, the beams of which extend longitudinally thereof and spiral torsional braces embedded therein and extending in both directions the entire length of the hull and secured to the beams.

7. A concrete ship comprising a concrete metal reinforced hull, ribs, frames and beams extending longitudinally of the hull, and forming the reinforcement and spiral torsional braces embedded in the hull and extending in both directions and tied to the ribs, frame and beams at the point of intersection.

8. A concrete ship comprising longitudinal beams, frames, ribs, spirally arranged torsional braces tied to the frame, ribs and beams, said ribs, beams and braces formed of reinforced concrete and a metal reinforced concrete inner and outer skin inclosing the ribs, beams, frame and braces having spaces between the same as shown.

9. A concrete ship comprising longitudinal beams, frame, ribs and spirally arranged torsional braces tied to the frame, ribs and beams and inclosed in concrete, and an inner and outer skin inclosing the ribs, frame, beams and braces substantially as shown.

10. A concrete ship comprising a concrete metal reinforced hull having spiral torsional braces embedded in the sides, bottom and deck of the hull.

11. A concrete ship comprising a concrete metal reinforced hull having spiral tor-

sional braces embedded therein and extending entirely around the hull intersecting the keel and the deck.

12. A concrete ship comprising a concrete metal reinforced hull having spiral torsional braces extending in both directions from bow to the stern and embedded in the hull and intersecting the keel and the deck.

13. A concrete ship comprising a concrete metal reinforced hull having spiral torsional braces extending in both directions from the bow to the stern and intersecting the deck beams and the keel.

14. A concrete ship comprising a concrete metal reinforced hull having longitudinal beams in the hull and deck, spiral torsional braces extending in both directions from the bow to the stern and intersecting the beams and the bars of the beams welded to the bars of the torsional braces.

15. A concrete ship comprising a concrete metal reinforced hull having longitudinal beams, ribs, frames, spirally arranged braces extending from the bow to the stern and intersecting the beams, ribs, frames and having reinforcement thereof welded together at the points of intersections and transverse bulkheads dividing the ship into several transverse compartments.

16. A concrete ship comprising a concrete metal reinforced hull having longitudinal beams, ribs and frames extending from the keel upwardly to a point in a plane with the deck, deck beams extending longitudinally and connecting the side of the ship, and spiral torsional braces intersecting the hull beams and deck beams and extending entirely around the ship in both directions.

17. A concrete ship comprising a concrete metal reinforced hull having hatch openings, metal reinforced rings surrounding the hatch openings, and spiral torsional braces embedded in the concrete of the hull and the braces intersecting said openings secured to the rings.

18. A concrete ship comprising a concrete metal reinforced hull, and a series of continuous spiral torsional braces embedded therein and extending from the bow to the stern.

19. A concrete ship comprising a concrete metal reinforced hull, and a series of spiral torsional braces embedded therein and extending in both directions from the bow to the stern in a continuous line.

20. A concrete ship comprising a concrete metal reinforced hull, the beams of which extend longitudinally thereof, and spiral torsional braces embedded therein and extending in both directions, and tied to the beams and extending in a continuous line from the bow to the stern.

21. A concrete ship comprising a concrete metal reinforced hull having hatch openings, rings surrounding the hatch openings, and

spiral torsional braces embedded in the concrete of the hull and the braces intersecting said openings secured to the rings.

22. A concrete ship comprising a concrete metal reinforced hull having hatch openings, beams, rings surrounding said hatch openings, and continuous spiral torsional braces embedded in the concrete of the hull

and tied to the hull, and the braces intersecting said openings secured to the rings.

In testimony whereof, I affix my signature, in the presence of two witnesses.

JAMES R. WALSH.
